Patented Jan. 6, 1920.

INVENTOR:

James A. Motsenbocker,
B. Frank H. Woerner,
ATTORNEY.

UNITED STATES PATENT OFFICE.

JAMES A. MOTSENBOCKER, OF INDIANAPOLIS, INDIANA, ASSIGNOR OF ONE-HALF TO
EMIL F. BURKLE, OF INDIANAPOLIS, INDIANA.

AMUSEMENT APPARATUS.

1,326,954.

Specification of Letters Patent.

Patented Jan. 6, 1920.

Application filed April 21, 1919. Serial No. 291,499.

To all whom it may concern:

Be it known that I, JAMES A. MOTSENBOCKER, a citizen of the United States, residing at Indianapolis, in the county of Marion and State of Indiana, have invented certain new and useful Improvements in Amusement Apparatus, of which the following is a specification.

This invention relates to an amusement apparatus; and one of the objects of the invention consists in the provision of a portable amusement device which is adapted for both indoor and outdoor places of amusement, and one which promotes healthful exercise for the participants.

A further object of the invention consists in the provision of an amusement apparatus which is simple in construction, inexpensive to manufacture and one which stimulates zeal and zest among the participants.

I accomplish the above objects of the invention, and such others as may appear from a perusal of the following description and claims, by means of the construction illustrated in the accompanying drawings, forming a part hereof, in which—

Figure 1 is a perspective view of my improved amusement apparatus. Fig. 2 is a longitudinal sectional view through the apparatus, on a slightly enlarged scale. Fig. 3 is a fragmentary detail longitudinal sectional view through the ball chute.

Referring to the drawings, the amusement apparatus comprises a portable rectangular frame consisting of four upright posts 10 one of which is arranged at each corner, the said posts being joined together by means of the longitudinal connecting rails 11, the cross rail 12, and the ball chute 23. The space within the four posts 10 and above the connecting rails 11 is inclosed on the sides by means of canvas 15 or similar material, and the end of the apparatus opposite the players' end with canvas 16, which define the field area within which the balls 17 are rolled in playing the game. A canvas 18 is arranged upon the connecting rails 11 to form a floor and closes the bottom of the field area described by the side and end walls 15 and 16. The end of the apparatus next to the player is closed between posts 10 by a wire netting 19 so as not to obscure the visibility of players in observing the course of the balls' travel along floor 18. Connecting rails 11 and floor 18 are placed

in an inclined position so that balls 17 when thrown and strike the forward wall 16 they will rebound and light upon and be deflected back to the players' end of the apparatus by means of the inclination imparted to said floor 18. The normal surface plane of floor 18 may be disturbed by introducing therein one or more steps, as at 20, which has a tendency to change or deflect the return course of the thrown balls and thereby inject more uncertainty as to the ultimate course taken and the final resting positions assumed by the returning balls when they reach the players' end of the apparatus. When the returning balls 17 reach the foot of floor 18 they come to rest upon a trap-door 22 which normally occupies a horizontal position and closes an opening leading into a ball chute 23. In order to promote interest in the game prizes are usually given to the player having the greatest number of balls occupying a given number of similarly colored pockets, and these pockets are formed above trap-door 22 by means of a series of transverse partition walls 25 which extend transversely across the mouth leading into ball chute 23. These pockets are arranged arbitrarily in series, of which each series contains a uniform number of pockets, and each pocket in a series has a different color, which color scheme is carried out through the different series, so that it is possible for a player to have two or all of the balls allotted to him to enter pockets of like color, thereby enabling the ratio of the number of balls allotted a player to determine the value of the prize. After a player's turn at play with all spent balls resting upon trap-door 22 they are simultaneously discharged into ball chute 23 when trap-door 22 is depressed. The floor sections 26 and 27 of the ball chute are arranged in descending planes toward the center of the apparatus so that the balls are directed toward a common discharge opening 28 and into a receiving receptacle 29 below, where they are available to the players. Trap-door 22 is pivotally mounted by means of one or more hinges 30 and is actuated downwardly by means of a foot-lever 31 which is pivotally secured at 32 to a support 33, the lever 31 being connected to a trap-door 22 by means of a connecting rod 35. Trap-door 22 is normally held in a horizontal position so as to keep the mouth of ball chute 23 closed by means of a spring 110

37 which connects lever 31 to the frame of the apparatus, the tendency of said spring being to exert a pull upon said lever. Lever 31 is arranged generally at the players' end 5 of the apparatus so as to be readily accessible and can be actuated by anyone of the players.

Arranged transversely between posts 10 at the players' end of the field, and usually 10 about midway between trap-door 22 and the upper ends of said posts, is a shelf 40 upon which prizes may be displayed for attracting the public's attention to the apparatus, and at the end of the apparatus opposite the 15 players' end, and usually above the end wall 16, I provide certain means 41 for the display of suitable advertising matter as may be deemed appropriate or desirable for attracting customers when conducting the 20 game either for pleasure or for profit.

Having thus fully described my said invention, what I desire to secure by Letters Patent, is—

1. An amusement apparatus comprising 25 an inclined field for returning the spent balls to the players, means for disarranging the normal surface plane of the field for deflecting the course of the returning balls, means for inclosing said field and keeping 30 the balls in defined limits, a series of pockets arranged along the foot of the field for receiving the spent balls, a trap-door for

supporting the spent balls, means for depressing and effecting the discharge of the spent balls from the pockets, a ball chute 35 for receiving the balls discharged from the end of the field and conveying them to a common discharge opening, and means for receiving the collected balls.

2. An amusement apparatus comprising 40 an inclined field for returning the spent balls to the players, means for disarranging the normal surface plane of the field for deflecting the course of the returning balls, means for inclosing said field and keeping 45 the balls in defined limits, a plurality of pockets arranged at the foot of the field for receiving the spent balls, said pockets being arranged in groups comprising a uniform number of differently colored pockets in 50 which the color scheme of one group corresponds to that employed in the other groups, a trap-door for temporarily supporting the spent balls occupying the pockets, means for actuating the door for effecting the discharge of the spent balls, and a ball chute 55 for catching and for conveying the discharged balls to a common discharge opening.

In witness whereof I have hereunto set my 60 hand and seal at Indianapolis, Indiana, this 17th day of April, A. D. one thousand nine hundred and nineteen.

JAMES A. MOTSENBOCKER. [L. S.]
